DESIGN FOR A DOG BED OR SIMILAR
ARTICLEPaul E. Shoemaker, Los Angeles, and Lyle L. Lewis, Sherman Oaks, Calif.

Application December 2, 1946, Serial No. 135,204

Term of patent 3½ years

(CL. D12—5)

To all whom it may concern:

Be it known that we, Paul E. Shoemaker and Lyle L. Lewis, citizens of the United States, residing, respectively, at Los Angeles and Sherman Oaks, in the county of Los Angeles and State of California, have invented a new, original, and ornamental Design for a Dog Bed or Similar Article, of which the following is a specification, reference being had to the accompanying drawings, forming a part thereof.

We claim:

The ornamental design for a dog bed or similar article, substantially as shown.

PAUL E. SHOEMAKER.
LYLE L. LEWIS.
